DESIGN FOR A CARD-SUSPENSION CLIP.

The Schedule referred to in these Letters Patent and making part of the same.

To all whom it may concern:

Be it known that I, GEORGE W. MCGILL, of the city, county, and State of New York, have invented and produced a new and original Design for a Card-Suspender, of which the following is a specification.

The nature of my design is fully represented in the accompanying drawing forming part of this specification, and consists in a piece of metal struck up so as to represent a hand holding a stirrup. The wrist of the hand is provided with lugs, and with a hole in its center to admit of the suspender being attached to

the article to be suspended either by means of the said lugs or by running one of my patent paper-fasteners through the hole in the wrist.

I claim as my invention—

The design for a card-suspender, as herein shown and described.
